TABLE STRUCTURE

Robert E. Schieber, Detroit, Mich.

Application November 19, 1936, Serial No. 111,562

12 Claims. (Cl. 311--18)

The invention relates to a table of the type adapted to be folded into a recess in the wall of a room when not in use.

One object of the invention is to provide a folding table of large size adapted to collapse into a relatively small wall recess.

Another object of the invention is to provide a table of the type mentioned having a top surface adapted to be folded upon itself when moved into the wall recess.

A further object of the invention is to provide a table adapted to be folded into an appropriate wall recess wherein the table top itself constitutes the closure element for said recess.

Another object of the invention is to provide a folding table of large size adapted to be folded and unfolded with a minimum of effort and without the necessity of supporting the weight of the table.

Another object of the invention is to provide an automatic locking means for holding the table in an operative position.

A further object of the invention is to provide a table of the type described which is simple, inexpensive to manufacture, light in weight and rugged in construction.

Other objects and advantages of the invention will become apparent upon reference to the accompanying drawings, specification and the claims hereinafter set forth.

Referring to the drawings wherein like numerals are applied to like parts in the several views:

Figure 1 is a perspective view of the table illustrating the manner in which it is folded or unfolded.

Figure 2 is a perspective view of the table in its unfolded or operative position.

Figures 3 and 4 are enlarged longitudinal sectional views of the inner and outer table sections, respectively.

Figure 5 is a horizontal section taken on the line 5--5 of Fig. 3 showing the automatic locking means for holding the table in its folded or inoperative position.

Figure 6 is a plan view of the table in operative position, with parts broken away and others in section.

Figure 7 is a transverse vertical section taken on the line 7--7 of Figure 6.

Figure 8 is a transverse vertical section taken on the line 8--8 of Fig. 6.

Figure 9 shows a fragmentary longitudinal vertical section taken on the line 9--9 of Figure 6.

Figure 10 is a horizontal section taken on the line 10--10 of Figure 9.

Figure 11 is a vertical section taken through the lock on the line 11--11 of Figure 6, on an enlarged scale.

Figure 12 is a fragmentary plan view of the lock.

Figure 13 illustrates one form of key which may be utilized for operating the lock.

Figure 14 shows a vertical section of the table in a partially folded condition.

Fig. 15 shows a vertical section of the table in its completely folded condition.

As shown best in Figures 1 and 2, the table comprises a pair of elongated sections indicated generally at 10 and 11, pivotally connected together at their adjacent ends and adapted to be collapsed into an opening indicated generally at 12 in a wall 13.

The table sections proper comprise a framework of angle iron members 14 upon which is secured a laminated top, the outer edges of which conform to the outer faces of the angle iron members. In the preferred form, shown in Figs. 3 and 4, the top comprises a layer of sheet metal 15 secured by rivets or welding to the horizontal flanges of the angle iron members, and a layer 16 of linoleum which is secured to the sheet metal layer by any suitable means such as an adhesive. As shown in Figs. 3 and 4, the sheet metal layer is provided with a series of spaced transversely extending channels or corrugations 17 for increasing its transverse rigidity. An edge finish strip 18 of aluminum or other suitable metal is secured to the outer face of the angle iron members. The finish strip extends entirely around both table sections and extends upwardly flush with the top surface of the linoleum.

It will be observed that this construction results in a light weight top of sturdy construction and having a top surface of material which deadens sound and is highly resistant to marring. If desired, additional sound deadening characteristics may be secured by providing a layer of pressed wood or the like between the linoleum and sheet metal layers as shown in Figures 5, 7, 8 and 11, or by substituting pressed wood for the sheet metal layer. If the sheet metal layer is not used, the angle iron members 14 are secured directly to the pressed wood layer by any suitable means such as countersunk flat headed rivets or bolts, and the under side of the table is reinforced by transverse members 19, as shown in Fig. 1.

The abutting ends of the two table sections 10 and 11 are hinged together by means of a hinge 20 having its hinge arms welded, riveted or otherwise permanently secured to the inner sides of 55

the end angle iron members 14, as shown in Figures 3 and 4. The hinge is so arranged that the top surfaces of the two table sections abut each other and lie in the same plane when the table 5 is unfolded and placed in its operative position.

When the table is folded it is adapted to be positioned within and close the recess 12 in the wall 13, which recess is provided with a sheet metal lining 30 covering the side wall, top wall, 10 back wall and a portion of the bottom wall of the recess. The side and top edges of the recess are reinforced by angle iron members 31, 32 and 33 which are welded or otherwise fixedly secured together at the top corners of the recess. Positioned 15 at opposite sides of the recess adjacent the lower portion thereof is a pair of plates 35, one of which is shown in Figures 3, 9 and 10. Referring particularly to Figure 10, it will be seen that the plates 35 are seated against the inner legs 20 of angle iron members 31 and 32 and at their rear edges seat upon a spacer member 36. A finish strip or bead 37 positioned inwardly of the angle iron members 31, 32 and 33 and flush with their outer surfaces, frames the recess and 25 extends over the forward edge of plates 35, as shown in Figure 10.

The constituent parts of the recess lining or frame, that is, the lining 30, angle iron members 31, 32 and 33, spacer member 36 and the finish strip 37 are permanently secured together preferably by welding, riveting or the like to form an integral unit adapted to be installed in the wall of a building as a permanent part thereof. In addition, this unit is provided with a plurality of 30 anchor bars 39 welded at spaced points along the inner faces of the angle irons 31, 32 and 33, and an angle iron 40 welded to the top of lining 30 and extending outwardly beyond the sides of the lining 30. The anchor bars 39 and angle iron 40 35 are embedded in the wall 13 to reinforce the recess lining frame. The plate members 35 may form a permanent part of the recess lining unit, if desired, but they are preferably secured in place by machine screws passing through the plate and 40 angle iron members 32 and 33 and spacer members 36 to facilitate installation.

Plate members 35 are provided with slots 40, the lower portions of which extend vertically while the upper portions incline upwardly and 45 outwardly of the recess, as shown best in Figure 3. In addition, plate members 35 are provided with vertically extending grooves in their rear faces for the reception of sliding latch members 41, shown best in Figures 9 and 10. The latch members 40 are adapted to fall by gravity in their 50 respective grooves across the adjacent slots 40 in the members 35; and pins 42 are provided to prevent complete withdrawal of the latches from their recesses.

The inward edge of the table top section 11 is provided with an end piece 49 secured by machine screws, rivets or by welding to the downwardly extending leg of the adjacent angle iron member 14; and a pair of pins 50, fixedly secured in the ends of the member 49, provide journals for a pair of rollers 51 which are positioned within the slots 40 of members 35. These rollers provide one connection between the table top and the 55 recess lining or frame structure, and movement of the rollers in the slots guides the table during its folding and unfolding movements. It will be observed that latch members 41 are adapted to fall by gravity into a position wherein they lock 60 the rollers at the upper ends of slots 40, thus

holding the adjacent end of the table in its operative position.

A yoke member 52 is journaled at its ends on plates 35 by means of pins fixedly secured to the downwardly extending ears 53 on yoke 52 and extending into suitable openings in the lower portions of the plate members. The yoke is provided at its mid point with a housing having a transverse bore in which is fixedly secured the end of a tubular strut member 54; and a pin 55 passing 10 through the yoke housing and strut prevents relative movement between the two. The opposite end of strut 54 is pivotally connected to the opposite end of table section 11. The latter connection comprises a bracket 56 secured to the 15 under side of the table section 11 at a point spaced inwardly from the outer end thereof by means of machine screws 57 passing through the inwardly extending flange on angle iron members 17. Bracket 56 is provided with four pairs of spaced 20 downwardly extending ears 58, through which is passed a rod 59. The upper or outer end of the tubular strut member 54 is provided with a yoke 60 having bifurcated arms, the ends of which are journaled on rod 59 at points between the respective 25 ears 58 of the outer pairs on bracket 56, as best shown in Figure 8. Yoke 60 includes a central longitudinally extending housing 61, having a bore in which is received the end of the tubular strut member 54, as shown in Figure 3; and this 30 end of the strut is provided with interior threads adapted to receive a threaded adjusting plug 62, which has a reduced end portion 63 passing freely through the end of housing 61. The reduced end portion 63 of plug 62 is provided with a slot for 35 engagement with a screw driver for the purpose of adjusting the position of the ends of strut 54 with respect to housing 61, and thus adjusting the elevation of the outer end of the table section 11. A nut 64 is threaded on the reduced end section 63 of the adjusting plug for the purpose of holding the shoulder on plug 62 against the bottom of the bore in the housing 61 and locking the parts in adjusted position.

The outer end of the table section 10 is supported 45 by means of a leg structure comprising a frame having a pair of spaced upright members 70 and 71 connected by horizontal transverse members 72 and 73, which have intermediate offset portions 74 and 75, respectively, to accommodate the strut member 54 when the table is folded. The upright members 70 and 71 are curved outwardly above the upper horizontal member 73, as shown in Figure 7, and terminate in vertically extending portions journaled respectively on pins 76 and 77, carried by downwardly extending ears 78 and 79 on a horizontally extending bracket member 80. Pins 76 and 77 50 may take the form of headed bolt-like members, as shown in Figure 7, in which case they may be held against axial movement with respect to the ears 78 and 79 by means of cotter pins and washers at the headless ends thereof. Bracket member 80 is secured to the underside of the table section 10 by means of screws 81 passing into the 55 horizontal flange on the angle iron members 17, or the bracket 80 may be welded to the angle iron members and spot welded to the sheet metal layer 15, if desired.

The lower ends of the upright leg members 70 70 and 71 are curved outwardly and terminate in vertical cylindrical housings 85 and 86, in each of which is journaled the trunnion of a pivotally mounted wheel unit, indicated generally at 87 and 88 respectively. The elevation of the outer 75

end of table section 10 may be adjusted by means of the cap screws 89 and 90, which are threaded into the upper ends of housings 85 and 86, respectively, and bear upon the ends of the wheel unit 5 trunnions. Lock nuts are provided for fixing the cap screws 89 and 90 in adjusted position. In use the wheel units 87 and 88 are not intended to function as caster wheels, but are fixed against rotation about their trunnion axes in a slightly 10 toed-in position by means of cap screws 91 and 92. This slightly toed-in position of the wheels guides the outer end of a table in a straight line as the table is folded and unfolded. It is apparent that if adjustments in the alignment of these 15 wheels are desired, it can be accomplished by loosening the cap screws 91 and 92 and turning the wheels to the desired position.

Means are provided for automatically folding the leg frame structure, just described, against 20 the under side of the table section 10, as the table is folded into the wall recess. This means, as best shown in Figures 4, 6 and 7, comprises a pair of links 100 and 101, each of which is pivotally secured at one end to one of the upright leg 25 members 70 or 71 by means of a cap screw 102 having a shoulder thereon, as shown in Figure 7, for spacing the head from the adjacent upright member and preventing binding of the pivotal connection. The upper ends of link members 100 30 and 101 are journaled upon the outer ends of a pair of pins 103 and 104 respectively, which are carried respectively in longitudinally extending slots in a pair of longitudinal frame members 105 35 and 106. Frame members 105 and 106 are secured at their outer ends by cap screws 110 to an elongated horizontal flange 111 on the end angle iron 14, and are secured by similar screws 112 at their inner ends to the bracket member 80 upon which the leg frame structure is pivoted. Upon the 40 inner ends of pins 103 and 104 are journaled respectively the ends of a pair of elongated link members 115 and 116, the opposite ends of which are journaled on the rod 59 between the respective ears 58 of the inner pairs. As indicated 45 in Fig. 3, links 115 and 116 pass through suitable slots in hinge 20 when the table is unfolded.

By reason of the structure just described, it is apparent that folding movement of the table top about hinge 20 will move rod 59 toward the outer 50 end of the table section 10. This movement is transmitted to pins 103 and 104 by means of links 115 and 116, respectively, thus moving pins 103 and 104 to the right in the slotted members 105 and 106. Such movement of the pins 103 and 104 55 effects, through links 100 and 101, a folding of the leg frame structure about the pivot pins 76 and 77, in the manner indicated in Figures 1, 14 and 15. The linkages are so arranged that when the table is folded entirely within the recess 12, the 60 leg frame structure will be collapsed substantially parallel with the table top section 10, as shown in Fig. 15, at which time it will overlie the tubular strut member 54, the offset portions 74 and 75 of transverse leg frame members 72 and 73 being provided to accommodate the tubular strut 65 member at this time, as previously mentioned. In addition, the rate of folding is such that the free end of table section 10 is always supported free of the floor by means of the wheels on the 70 leg structure. One of the advantages of this form of mechanism for folding the leg is that, except for the short links 100 at the outer end, all of the linkage lies close to the under side of the table. This is desirable since otherwise persons 75 seated at the table might place their feet on the

folding mechanism and mar or injure the same.

In addition to the function of folding the leg frame structure automatically during folding of the table, the structure just described performs that function in such a manner as to materially assist in the table folding operation. This follows from the fact that the leg frame folding links 115 and 116 are in effect connecting rods operated by a crank arm which in the unfolded position of the table extends in line with the links 115 and 116. 10 The crank arm in this case is that portion of the table top 11 between hinge 20 and rod 59. As a result of this arrangement the rod 59 during initial table folding movement moves approximately perpendicularly to the plane of table top 15 portion 10 and therefore causes very little folding movement of the leg frame structure with respect to top 10. Accordingly during initial table folding movement the leg frame structure remains substantially perpendicular to top 10 and 20 the floor engaging wheel units 87 and 88 will therefore be moved inwardly toward the wall. This materially increases the amount of table top 10 which overhangs the floor engaging wheel units; and the added overhanging weight assists 25 in elevating the inner end of the table top 10 during the early portion of the folding movement.

When the table is folded into the recess, the inner section 11 is automatically locked in place by the lock mechanism shown at the top of Figure 30 3 and in the section view of Figure 5. This lock mechanism comprises an L-shaped plate 120 permanently secured to the back wall of lining 30, as by a rivet 121. Member 120 is provided with a horizontally extending slot; and a double arm 35 latch member 123 is pivotally mounted within the slot by means of a vertically extending pin 124. The extremities of the double arm latch are spaced apart slightly more than the width of finish strip 18 on the table top and are curved 40 inwardly of the recess in such a manner that, regardless of the pivotal movement of the latch about pin 124, at least one of the arms has its extremity projecting into the path of the movement 45 of the table top sections.

As the result of the arrangement just described, the latch mechanism operates in the following manner. As the table is folded inwardly from the position shown in Figure 1, the outer edge of the inner table top section 11 first passes the extremity 126 on latch 123 and then the extremity 125 on the latch member until it assumes the position shown in Figure 5. During this movement, the latch is cammed out of the way by its inclined end surfaces and freely rotates first to a 50 position wherein extremity 126 is out of the path of movement of table top section 11 and then to the position wherein the opposite extremity 125 is 55 out of that path. Further collapsing movement of the table top swings the outer section 10 about its hinge connection 20 with the table top section 11 until the side edge of section 10 engages the extremity 126 of the latch member, forcing it into slot 122, as shown in Figure 5. This results in a pivotal movement of the latch 123 to a position wherein the extremity 125 locks inner table top section 11 against outward movement. It will be observed that the lock mechanism just described automatically locks the table top section 11 in its folded position and that the latch can 60 only be released by a predetermined outward pivotal movement of the table top section 10 about its hinge connection 20 with the section 11.

In Figures 11, 12 and 13 is shown a locking 65 means for securing the outer table top section 70

10 within the recess. This means comprises a rotatable locking member 130 journaled in the table top section 10 on a bushing 131. Member 130 and bushing 131 terminate flush with the 5 top surface of the table, and hence do not interfere with the normal using of the table and do not present a projection upon which persons might be injured when the table is folded within its recess. The under side of rotatable locking 10 member 130 has an outwardly extending flange 132 underlying the table top and carrying a pair of diametrically opposed vertically extending pins 133 and 134, to which are pivotally connected the ends of a pair of oppositely directed locking rods 135 and 136. As best shown in Figures 6, 11, and 12, the transverse bracket member 30 upon which the leg structure is pivoted has an inwardly extending projection 137 which underlies and provides a housing for the rotatable locking member 130. The housing is provided with a pair of oppositely directed lateral slots 138 and 139 through which the locking rods 135 and 136 extend, respectively. The outer extremities of the locking rods 135 and 136 extend through 25 suitable openings in the angle iron side members 17 and 18 and are adapted, when the rotatable locking member 130 is rotated, to project beyond the outer faces of finish strips 18 and to engage in suitable openings 140 in the plate members 30 35 of the recess to lock the outer table section 10 within the recess.

While any suitable means, such as a handle, may be utilized to rotate the lock member 130, in the preferred form shown in the drawings this 35 rotation is effected by a removable key, shown in Figure 13, which may be inserted within a key slot 141 in member 130 for rotating the same. The slot 141 in the rotatable locking member 130 is provided with an enlarged portion inwardly of 40 the exposed face of member 130. This enlargement of the inner end of the slot defines a pair of shoulders 142 and 143 extending in a plane parallel to the table top. By reference to Figure 12, it will be seen that the enlarged inner 45 section of slot 141 has its side walls parallel to each other but positioned at an angle with respect to the side walls of the entrance portion of slot 141, with the result that the shoulders 142 and 143 formed at the juncture of the two slot portions are triangular in shape.

The key shown in Figure 13 is provided with a pair of oppositely disposed transverse grooves 150 and 151 adjacent its ends, which define shoulders 152 and 153. It will be seen that when the key is inserted into slot 141 and rotated in a clockwise direction to unlock the table top section 10, the shoulders 152 and 153 will engage under the shoulders 142 and 143 in the slot of the locking member 130. Such inter-engagement of the shoulders on the key and on the locking member prevents withdrawal of the key, with the result that the key may be utilized to pull the table top section 10 out of the recess. However, when the key is rotated in the opposite 60 direction to lock the table top in position within the recess, shoulders 152 and 153 cannot engage under the shoulders 142 and 143 in the locking member, and thus when the locking is completed the key may be easily withdrawn.

70 It will be observed from the above description that there is provided, in accordance with this invention, a relatively simple folding table of large size adapted to form a permanent part of the wall of a room, and which is very easily folded or unfolded into a recess in the wall. When the 75

table is installed, it may be readily adjusted to a level position regardless of irregularities in the floor by means of the adjusting plug 162 on the strut member 55 and the adjusting cap screws 89 and 90 on the wheel units 87 and 88. Once this adjustment is made for any given installation, there is ordinarily no necessity for further adjustment during the life of the table.

When it is desired to fold the table from the position shown in Figure 2, it is only necessary 10 to lift latch members 41 whereupon the weight of the table top section 11 will cause it to fall downwardly to a slight extent, guided by the rollers 52 in slots 40 of the plate members 35. As soon as the rollers have moved downwardly from 15 the position shown in Figure 9, the latch members 41 may be released since they cannot thereafter fall back into locking position. It will be observed that the weight of the inner end of the table top section 11, in causing that end of the 20 section to drop downwardly, tends to elevate the outer end of the section 11, the hinge connection 20, and the inner end of the table top section 10. This initiates the folding, and increases the amount of overhang of top 10 over wheel 25 units 87 and 88 as previously described, accordingly the folding action can be completed by a relatively light inward push on the outer extremity of the outer table section 10. It will be noted that at no time is it necessary to support the weight of any portion of the table when 30 folding or unfolding the same inasmuch as the supporting wheels always remain in contact with the floor.

As the sections move into the recess, latch 123 35 locks the inner table section 11 against outward swinging movement and thus prevents accidental unfolding of the table. The outer section 10 is then locked in position by means of the key and locking mechanism shown in Figures 10, 11, 12 and 13. In the completely folded position, the 40 recess is closed by the table top section 10, which lies substantially flush with the wall and presents no projections upon which persons may catch their clothing or against which they might collide. This is important inasmuch as one field of use for the table is in connection with schools where it is desired to use a given floor space alternatively for a lunch or study room and a play room, and projections from the wall of a children's play room are a source of danger. 50

What is claimed is:

1. In a folding table construction or the like, a supporting member, a table or the like including a pair of top sections pivotally connected together for movement into a common plane with their edges in abutment, means connecting one of the sections to said support for swinging movement from a horizontal position into a vertical position, a supporting leg pivotally secured to the other section, floor engaging rolling means carried by said leg, and means for positively swinging said leg toward the plane of the other section as the sections are folded together. 55
2. In a folding table construction or the like, a supporting member, a table or the like including a pair of top sections pivotally connected together for movement into a common plane with their edges in abutment, means connecting one of the sections to said support for swinging movement from a horizontal position into a vertical position, a supporting leg pivoted at one end to the under side of the other top section, floor engaging rolling means at the opposite end of said leg, and means for automatically swing- 70 75 75

ing said leg toward the plane of said other top section as the rolling means moves along the floor during folding movement.

3. In a folding table construction or the like, a supporting member, a table or the like including a pair of top sections pivotally connected together for movement into a common plane with their edges in abutment, means connecting one of the sections to said support for swinging movement from a horizontal position into a vertical position, a supporting leg pivotally secured to the other section, floor engaging rolling means carried by said leg, and means for swinging said leg toward the plane of said other section of the table as the table is folded, said last mentioned means including a link pivotally connected at one end to the first top section at a point spaced from the axis of the pivotal connection between said sections and operatively connected at its opposite end to said leg at a point spaced thereon from the axis of the leg pivot.

4. In a folding table construction or the like, a supporting member, a pair of top sections pivotally connected together for movement into a common plane in edge-to-edge abutment, means connecting one of said top sections to said supporting member for combined rotary and translatory movement from a horizontal position spaced from the floor to a substantially vertical position with one edge adjacent the floor, and floor engaging means for supporting the other top section and guiding said sections in their folding movement.

5. In a folding table construction or the like, a supporting means, a pair of top sections pivotally connected together for movement into a common plane in edge to edge abutment, means connecting one of said top sections to said supporting member for combined rotary and translatory movement from a horizontal position spaced from the floor to a substantially vertical position with one edge adjacent the floor, and floor engaging means for supporting the other top section and guiding said sections in their folding movement, said floor engaging means being pivoted to said other section, and means for automatically folding said floor engaging means towards the plane of said other section as the sections are folded together.

6. In a folding table construction or the like, a supporting member having an upwardly extending slot, a top comprising a pair of sections pivoted together for movement into a common plane with their adjacent edges in abutment, means on one of said top sections adjacent its free edge for engaging in said slot, a strut member pivoted at one end to said supporting member and at the opposite end to said one top section adjacent the abutting edge thereof, and a rolling support for the other top section.

7. In combination, a wall having a recess therein, a table top or the like including a pair of sections pivoted together for movement from a common horizontal plane into overlapping relation in spaced substantially parallel vertical planes, means connecting the free edge of one section to said wall for a swinging movement into said recess with the opposite edge thereof adjacent the upper end of the recess, and latch means for locking said one section in said recess,

said latch means being operated automatically by the other section as it swings about the pivotal connection between said sections and into said recess.

8. In combination, a wall having a recess therein, a table top or the like including a pair of sections pivoted together, means for connecting said top sections to the wall for movement into said recess with the two sections folded over one another in spaced substantially parallel vertical planes, automatic means for locking the innermost section within the recess independently of the outer section, said means being operated when the outermost section moves into said recess, and additional means for locking the outermost section in said recess.

9. In a folding table construction or the like, a supporting member, a table top or the like formed of two sections pivotally secured together, means for pivotally connecting one of said sections to said support at a point adjacent the edge remote from the other section, a strut member pivoted to said support and to the opposite edge of said one section, and a rolling support for the other section adapted to guide said sections in their folding movement, said strut and said rolling support being adjustable for leveling the top sections.

10. In a folding table construction, a supporting member having an upwardly extending slot therein, a table top having means adjacent one edge for engaging in said slot, releasable means associated with said member for holding said edge of the table at table height, a second table top pivoted to the opposite edge of said first table top, a rolling support for the outer end of said second table top, and a strut pivoted to said support and to the first table top adjacent its outer end whereby the weight of the inner end of the first table top tends to cause said table top sections to buckle upwardly about their pivotal connection.

11. In a folding table construction, a supporting member having an upwardly extending slot therein, a table top having means adjacent one edge for engaging in said slot, releasable means associated with said member for holding said edge of the table at table height, a second table top pivoted to the opposite edge of said first table top, a rolling support for the outer end of said second table top, and a strut pivoted to said support and to the first table top adjacent its outer end whereby the weight of the inner end of the first table top tends to cause said table top sections to buckle upwardly about their pivotal connection, said strut being adjustable in length to permit leveling of said table tops.

12. In a folding table construction or the like, a supporting member having an upwardly extending slot, a top comprising a pair of sections pivoted together at their ends for movement into a common plane with their adjacent ends in abutment, means on one of said top sections adjacent its free end for engaging in said slot, a strut member pivoted at one end to said supporting member and at the opposite end to said one top section intermediate the ends of the latter, and a rolling support for the other top section.
